UNITED STATES PATENT OFFICE

149,940

DESIGN FOR A TOY BOX

Bernard J. Greenbaum, Westport, Conn.

Application May 25, 1946, Serial No. 130,071

Term of patent 14 years

(Cl. D34—15)

To all whom it may concern:

Be it known that I, Bernard J. Greenbaum, a citizen of the United States of America, and a resident of Westport, county of Fairfield, and State of Connecticut, have invented a new, original, and ornamental Design for a Toy Box, of which the following is a specification, reference being had to the accompanying drawing, forming part thereof, in which—

Fig. 1 is a perspective view of a toy box with the cover closed.

Fig. 2 is a perspective view of a toy box with the cover open.

The end of the toy box opposite to that shown is identical therewith and the back is plain and unornamented.

I claim:

The ornamental design for a toy box, as shown and described.

BERNARD J. GREENBAUM.
